BY HER ATTORNEY

Martin Kaufmann

UNITED STATES PATENT OFFICE

IDA KAUFMANN, OF NEW YORK, N. Y.

LIP GUARD

Application filed March 21, 1932. Serial No. 600,253.

This invention relates to lip guards for roughest lips. It is the object of the present invention to provide an efficient device to protect ladies' dresses from discoloration by rouge on their lips when putting on or removing dresses.

It is another object of this invention to provide a device of this kind which is of sanitary construction and which is simple in its design and therefore can be made and sold for a very reasonable price.

It is another object of the invention to provide a device of the kind described which can be quickly put on or taken off by its wearer and which does not interfere with her breathing through the mouth.

With these and other objects in view, which will become clearer as the description progresses, the invention consists in a new article of manufacture embodying novel details of construction and arrangements of parts hereinafter more fully described and finally pointed out in the appended claims.

In the drawing which forms a material part of this disclosure:

Fig. 1 is a perspective front view of a lip guard embodying the invention when in operative position covering the mouth of the wearer.

Fig. 2 is a perspective view of a lip guard when not in service.

Fig. 3 is a detail front elevation of a part of the lip shield 11 illustrating the first step in its manufacture.

Fig. 4 is a detail elevation showing the shield 11 after the second step of its manufacture.

Fig. 5 is a detail elevation showing the shield 11 after the third and last step of its manufacture.

Fig. 6 is a sectional elevation on line 6—6 of Fig. 2.

Referring to the drawing, Figs. 1 and 2 show that the complete lip guard consists of two principal parts, namely a shield 11 which is adapted to cover the lips of the wearer and an elastic ribbon or strap 12, which is detachably fastened to opposite ends of shield 11 and is adapted to surround the head of the wearer, and thereby to hold shield

11 in its proper place to cover the wearers mouth. Shield 11 consists preferably of a single piece of silk-mohair ribbon or similar gauze-like fabric which is not too closely woven so as to permit easy breathing there-through and which is provided with selvages 13 or seams to furnish stiffened longitudinal edges. The transverse end portions 14 of shield 11 are folded backward into overlapping position as shown in Fig. 3 and then opposite corners 15 are folded to overlap each other and the center line of shield 11 as shown in Figs. 4 and 5 whereupon the male part 16 of a snap fastener is driven through the overlapping portions 15 and the fabric of 11, to hold the parts of shield 11 in their relative position shown in Fig. 5 and to form pointed ends 17 thereon.

The strap 12 consists preferably of a single piece of silk elastic ribbon curved as shown in Fig. 2 and provided near each end with the female part 18 of a snap fastener. The fastener-parts 18 are pressed on the co-operating parts 16 of shield 11 as shown in Fig. 2 and the whole lip guard adjusted 75 over the mouth of its wearer as shown in Fig. 1.

The red color of lip sticks is indelible and can not be removed from any fabric without seriously injuring the same and leaving ugly 80 stains. In dressmaking establishments, department stores and similar business houses, severe losses occur almost daily by the staining of valuable garments by touching the rouge on the lips of ladies who try on these 85 garments. The present invention furnishes a safe remedy, as it prevents the garments from coming in contact with rouged lips. The strap 12 can be used successively by several wearers, while a new shield is furnished 90 for every user of the lip guard for sanitary reasons.

While I have thus described a preferred form of my invention it shall be understood 95 that modifications may be made in the design and arrangement of parts, or in the construction of details which come within the scope and spirit of the invention as claimed.

Having thus described my invention, what 100

I claim as new and desire to secure by Letters Patent is:

1. A device of the kind described, comprising a shield consisting of a single piece of fabric adapted to assume the shape of the mouth of the wearer, said shield having stiffened longitudinal edges and being overlapped at its end portions, an elastic strap adapted to surround the head of a person and a single fastening means holding said overlapped portions together and adapted to engage means on said strap for quickly joining said shield to said strap.
2. A device of the character described comprising a flexible strap adapted to surround the head of the wearer, a snap fastener at each end of the strap, a shield member adapted to cover and conform to the shape of the mouth, said shield having turned over edges and overlapping ends, and securing means passing through the overlapped ends of the shield and protruding above the surface of the overlapped ends for engagement with the snap fasteners on the strap.
25. Signed at New York, in the County of Queens and State of New York this 16th day of March A. D. 1932.

IDA KAUFMANN.
